UNITED STATES PATENT OFFICE.

JOHN F. O'CONNOR, OF CHICAGO, ILLINOIS, ASSIGNOR TO WILLIAM H. MINER, OF CHAZY, NEW YORK.

ANTIFRICTION-BEARING.

1,357,809.

Specification of Letters Patent. Patented Nov. 2, 1920.

Application filed September 5, 1919, Serial No. 321,755.

To all whom it may concern:

Be it known that I, JOHN F. O'CONNOR, a citizen of the United States, residing at Chicago, in the county of Cook and State 5 of Illinois, have invented a certain new and useful Improvement in Antifriction-Bearings, of which the following is a full, clear, concise, and exact description, reference being had to the accompanying drawings, 10 forming a part of this specification.

This invention relates to improvements in anti-friction bearings.

The object of the invention is to provide a gravity controlled, self-centering anti-friction roller bearing adapted for use as 15 a side bearing on railway cars.

In the drawing forming a part of this specification, Figure 1 is a vertical sectional view taken through body and truck bolsters 20 of a railway car showing my improved bearing in connection therewith. Fig. 2 is a bottom plan view of the side bearing proper, parts being broken away in order to accommodate the view on the sheet. And 25 Fig. 3 is a vertical sectional view taken substantially on the line 3—3 of Fig. 1.

In said drawing, 10 denotes the upper portion of a truck bolster and 11 the under side of a body bolster of a railway car. I 30 have shown my improved bearing as applied to the truck bolster and, as shown, the same comprises broadly, a housing or retaining casting A, an anti-friction element B, a retaining and wear plate C, and guide blocks E.

The housing or base casting, as shown, 35 is of substantially hollow box form and has upwardly extended end walls 12—12, spaced side walls 13—13, and corner lugs 14—14 perforated to accommodate the rivets or other securing means. Said housing A is open at the top and the end walls thereof are provided with slots 15—15 to permit the insertion and removal of the plate C. The 40 latter is preferably made of case hardened steel and is prevented from accidental removal by any suitable means such as the cotters 16.

The anti-friction element B, as shown, 45 preferably comprises a solid cylindrical section referenced 17 adapted to have rolling bearing contact with the plate C and the under side of the body bolster or any suitable wear plate attached thereto. With this 50 construction, it is evident that I have a

true rolling action, and, as will hereinafter appear, the same is self-centering under the influence of gravity and without the aid of springs or other devices that would be likely to get out of order. Said anti-friction element B is provided at each end thereof, with depending, combined counterweights and centering lugs 18. Each of said lugs 18 is more or less wedge-shaped on its upper portion and has a rounded upper end 19 and 60 diverging flat edges 20—20, the latter being extended until the width of said lug in a direction transverse to the axis of the roller is substantially equal to the width of the guideway formed in the guide block E, 70 hereinafter described in detail. Below this point, each lug 18 is provided with a depending section, having a more or less rounded edge indicated at 21. The contours of the lugs 18 are made such that the 75 portions of the edges thereof presented to the vertical sides of the guide grooves in the block E will always either be closely adjacent thereto or in light contact therewith, without interfering with the true roll- 80 ing movement of the element B. The so-called guide block E is formed with up- standing side walls 22—22 adapted to be positioned between the ends of the roller section 17 and the side walls 13 of the base 85 casting A. Said side walls 22 are connected by integral cross bars 23—23 so located that they come just beneath the plate C and so that the latter will hold the block E in place when the parts are assembled. The 90 side walls 22 of the block E are recessed as indicated at 24 and provide vertical side guides coöperable with the lugs 18 as hereinbefore described. Said recesses 24 are de- 95 fined at their upper ends by substantially horizontally extending edges 25 so as to prevent the roller from being withdrawn when the parts are assembled.

The parts are assembled in the following manner: The lugs 18 are introduced into the recesses 24 by slipping the anti-friction element B upwardly through the opening in the bottom of the block E. The block E and element B are then inserted within the housing A. Then the plate C is intro- 100 duced through the slots 15 and the cotters applied so that all parts are thus held in assembled relation and in condition for application to the bolster. It will be noted 105 that the plate C bears on the raised bottom 110

D which is formed integral with the member A.

The operation of the side bearing is as follows. When the two bolsters approach each other in a vertical direction and radial movement therebetween occurs, pressure will be applied to the roller section 17 so as to roll to either side of normal position as for instance to the position indicated by the dotted lines in Fig. 1. During this rolling movement, the lugs 18 will be elevated within the recesses 24 but due to the configuration thereof, as above described, the movements of the lugs 18 within the recesses 24 will be unhampered until the final position indicated by the dotted lines is reached. Upon removal of the pressure from the anti-friction element, the lugs 18 will perform their function as counterweights and swing 20 or roll the element B back to its normal position. By employing the lugs 18 and associated guiding recesses 24, it is evident that the anti-friction element can not be bodily displaced by jarring or vibration by an amount greater than the small clearance left 25 between the edges of the lugs 18 and the vertical edges of the guiding recesses 24. In this manner, the bearing will always be in condition to perform its full travel 30 and the anti-friction element is positively self-centering without the aid of any springs or like devices which easily get out of order. It will also be noted that I obtain the true 35 rolling action but without the disadvantages usually attendant upon the employment of so-called rockers.

By forming the parts as shown, it is evident that all of the same, with the exception of the plate C, may be easily made in 40 the form of castings, preferably malleable castings. The plate C will generally be made of case hardened steel from plate material.

I claim:

45 1. In an anti-friction bearing of the character described, the combination with a retaining member, of an anti-friction element, said member having a bearing seat horizontal throughout and on which said element 50 bears and is adapted to roll to either side of normal position, said element having an eccentrically disposed weighted portion rigid with respect thereto, said weighted portion being elevated when the element has rolled 55 from its normal position in either direction and thereby adapted to roll said element in a return direction upon removal of the actuating force, and means, formed separately from the retaining member and disposed therein, coöperable with said weighted portion to guide the latter and limit the amount of off-center at which said element 60 may come to rest when free from actuating force.

65 2. In an anti-friction bearing of the char-

acter described, the combination with a retaining member, of an anti-friction element, said member having a bearing seat horizontal throughout and on which said element bears and is adapted to roll to either side of normal position, said element having eccentrically disposed weighted portions rigid with respect thereto, at each end thereof, said weighted portions being elevated when the element is rolled from its normal position in either direction and thereby adapted to roll said element in a return direction upon the removal of the actuating force, and means formed separately from the retaining member and disposed therein, coöperable with said weighted portions for guiding the latter and limiting the amount of off-center at which said element may come to rest when free from actuating force.

3. In an anti-friction bearing of the character described, the combination with a retaining member having a horizontal bearing seat, of an anti-friction element adapted to roll along said seat in either direction from normal and coöperating sets of means on said element and within said retaining member adapted to limit the amount of off-center of said element when the latter is free from actuating pressure, the portion of said means on the anti-friction element being 95 also adapted to return said element to normal position after actuation under the influence of gravity, the portion of said means within the retaining member being formed independently of the latter but assembled therewith.

4. In an anti-friction bearing of the character described, the combination with a base casting having a horizontal bearing seat, of an anti-friction element adapted to roll along said seat in either direction from normal, a separate recessed guiding block mounted within said base casting, and a combined counterweight and centering lug rigid with respect to said element and coöperable with said recessed guiding block to positively center the anti-friction element, under the influence of gravity, upon removal of the actuating pressure.

5. In an anti-friction bearing of the character described, the combination with a base casting having a horizontal bearing seat, of a cylindrical anti-friction element adapted to roll along said seat in either direction from normal, a detachable block mounted within said base casting and having recesses forming guides at opposite sides thereof, and combined counterweights and centering lugs at the ends of said roller disposed within said guides, the width of said 115 lugs, transversely of the guides, in any position of said lugs, approximating the transverse width of said guides.

6. In a side bearing of the character described, the combination with a hollow base 130

casting adapted to be secured to a bolster, of a block having upstanding spaced side walls mounted within said casting, said side walls being recessed to form guides, a removable bearing plate mounted in said base casting and adapted to hold said block in place when the parts are assembled, and an anti-friction roller supported on said plate, said roller having lugs at each end thereof eccentric-

ally disposed with respect to the roller, 10 said lugs being mounted within said guides and coöperable with the latter to limit the off-center of the roller.

In witness that I claim the foregoing I have hereunto subscribed my name this 20th 15 day of Aug., 1919.

JOHN F. O'CONNOR.
